CLAIM

The ornamental design for a wall mounted arm strength exerciser, as shown and described.

DESCRIPTION

FIG. 1 is a front, right, and top perspective view of a wall mounted arm strength exerciser, wherein at least one weight is on a lower part of a rod, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1 comprising gears.

FIG. 10 is a partial enlarged view of an area labeled 10 in FIG. 1 comprising hooks.

FIG. 11 is a partial enlarged view of an area labeled 11 in FIG. 1 comprising a part of a handle; and,

FIG. 12 is another front, right, and top perspective view of the wall mounted arm strength exerciser of FIG. 1, wherein the weight body is in an elevated state.

The broken lines shown in the drawings are included for the purpose of illustrating portions of the wall mounted arm strength exerciser that form no part of the claimed design.
